UNITED STATES PATENT OFFICE.

JOHN W. PITTS, OF CHICAGO, ILLINOIS, ASSIGNOR OF ONE-FOURTH TO ELSIE STRONG,
OF CHICAGO, ILLINOIS.

PLATE-HOOK FOR ROTARY PRESSES.

1,247,574.

Specification of Letters Patent.

Patented Nov. 20, 1917.

Application filed December 22, 1915. Serial No. 68,171.

To all whom it may concern:

Be it known that I, JOHN W. PITTS, a citizen of the United States, residing at Chicago, in the county of Cook and State of Illinois, have invented new and useful Improvements in Plate-Hooks for Rotary Presses, of which the following is a specification, reference being had to the accompanying drawings, forming a part thereof.

10 This invention relates to a device known as a plate hook and used for temporarily attaching a printing plate to a suitable bed provided in the printing press and adapted to hold the plate in operative position for printing. It consists of the features and elements described and shown in the drawings as indicated by the claims.

In the drawings:—

20 Figure 1 is a side elevation of the cylindrical bed of a so-called rotary press showing a printing plate attached to such cylindrical bed by means of plate hooks embodying this invention.

Fig. 2 is a top plan view of one of the 25 plate hooks.

Fig. 3 is a longitudinal vertical section taken as indicated at line, 3—3, on Fig. 2.

Fig. 4 is a transverse vertical section taken as indicated at line, 4—4, on Fig. 3.

30 The plate hook which is the subject of this invention is applicable to both flat bed and cylindrical bed presses, but more commonly the flat bed press is designed to receive type of standard type height, and printing plates which are not themselves of type height are therefore necessarily mounted upon suitable blocks to bring them to the level of the other type faces in the bed. When the bed is cylindrical, however, it is

40 not usually expected to receive ordinary unit type, but the printing is done from plates of comparatively slight thickness which are secured to the surface of the cylinder. Such a cylinder is indicated at A in Fig. 1 and

45 is formed with spirally-disposed grooves, B, which for the purposes of the present invention need only be of rectangular cross-section and are uniformly spaced over the cylindrical surface of the drum, A. The

50 general character of the plate hook employed for securing the printing plate, C, on the cylinder, A, is similar to that illustrated in Patent No. 1,043,105, dated November 5, 1912, as may be seen by a comparison of Fig. 3 with the drawings of said pat-

ent. The plate hook comprises a body, D, whose width is such that said body will fit snugly in any one of the slots, B, in the cylinder, A, and whose height is sufficient to bring the adjustable hook member, E, in position to engage the beveled edge, C¹, of the plate C. Each of the grooves, B, in the cylinder, A, has a series of small holes, B¹, drilled at regular intervals in the bottom of the groove, and the body, D, is provided at one end with a downwardly-projecting stud or pin, F, dimensioned to just fit in one of said holes, B¹, for anchoring the body, D, and the plate hook which it carries at any desired longitudinal position in the slot, B.

Preferably this stud or pin, F, constitutes simply the lower end of the screw, G, mounted for vertical adjustment in the end of the body block, D, and having a square socket, G¹, in its upper end to receive a suitable wrench for effecting such adjustment. Intermediate its ends the screw, G, is tapered at G², and this tapered portion engages the inner ends or heads, H¹, of pins, H, mounted to be thrust laterally outward through the side walls of the block, D, and having obtusely pointed outer ends, H², intended for engaging the side walls of the groove, B. Preferably the cylinder, A, is of cast iron, while the thrust pins, H, are of hardened steel so that their points, H², may even indent the side walls of the groove, B, for securing firm engagement therewith. The purpose of such engagement is partly to supplement the engagement of the stud, F, with the hole, B¹, but primarily to prevent the block, D, from coming out of the groove, B, in radial direction with respect to the drum, A, as it might otherwise do, either under the action of gravity when rotated to the lower side of the drum, or under the action of centrifugal force during rapid rotation of said drum.

By comparing the distance between the upper end of the screw, G, and the top surface of the block, D, with the distance of protrusion of the lower end, F, of the screw from the block, D, it will be seen that even when the screw is turned back to bring its upper end flush with the top of the block at which position the pins, H, will be released from engagement with the side walls of the groove, B, there will still be a short portion of the stud, F, extending from the bottom of the block, D. This, while perhaps

not sufficient to be relied upon completely for holding the block against longitudinal displacement, is sufficient to enable the operator to find the proper hole, B^1 , in the 5 groove, B , with which to engage the stud, F , in re-adjusting or re-setting the block, D , said hole being located merely by feeling for it with the protruding end of the stud, F , as the block, D , is moved along the groove 10 B . When the proper position for the block is found, it is only necessary to set down the screw, G , whereby the stud, F , is inserted farther into the aperture, B^1 , and the pins, H , are simultaneously thrust outward 15 by the wedging action of the tapered portion, G^2 , causing them to forcibly grip the side walls of the groove, B .

It will be understood that such positioning of the block, D , will bring the plate hook, E , approximately in holding position 20 with respect to the beveled edge, C^1 , of the plate, C . The final locking position of the hook, E , is effected by inserting a squared wrench member into the square 25 socket, J^1 , of the screw, J , which, as shown in Fig. 3, operates against the inclined plane, D^1 , forming a part of the interior bottom 30 wall of the block, D . As more thoroughly described in Patent No. 1,043,105, the reaction of the screw, J , against the inclined plane, D^1 , serves to force the jaw 35 or hook, E , longitudinally in its guide-ways, D^2 , in the block, D , and into final holding engagement with the beveled edge of the plate, C .

By reason of the spiral arrangement of the grooves, B , on the cylinder, A , the hook or jaw, E , must trend obliquely with respect 40 to the body block, D , and it is also necessary to make the plate hooks as rights and lefts—that is, with their jaw members, E , trending in oppositely oblique directions for use 45 on the sides and ends respectively, of the plate. In the plate hook shown in the above mentioned patent, the portion of the jaw member, E , which engages the guide grooves, D^2 , is shown as circular, thus permitting any angular adjustment of the jaw member with respect to the block; but such 50 circular form is undesirable, in that it permits the jaw to become completely reversed within the block, whereas in reversed position it would be inoperative. In the present construction, therefore, the sides, E^1 , 55 of the hook or jaw member, E , are curved as indicated in Fig. 2 to permit limited rotation of the jaw between the side walls of the block, D , but preventing complete rotation or reversal of the jaw within the 60 block. This permits the jaw, E , to accommodate itself to any inaccuracy in the edge of the plate, C , and would permit intentional oblique mounting of the plate on the drum, A , within certain limits, if desired.

I claim:—

1. In combination with a printing press having a rectangular groove in its bed and a series of holes disposed at intervals in the bottom of such groove; a plate hook for securing a printing plate on said bed, comprising a body block formed to fit in said groove; means projecting from the bottom of the block to engage one of said holes in the groove bottom; gripping means adapted for protrusion from the sides of the block to engage the side walls of the groove, and means for protruding or releasing said gripping means at will.

2. In combination with a printing press having a rectangular groove in its bed and a series of holes disposed at intervals in the bottom of such groove; a plate hook for securing a printing plate on said bed, comprising a body block formed to fit in said groove; means projecting from the bottom of the block to engage one of said holes in the groove bottom; gripping pins adapted for protrusion from the sides of the block to engage the side walls of the groove, and means for protruding or releasing said gripping pins at will.

3. In combination with a printing press having a rectangular groove in its bed and a series of holes disposed at intervals in the bottom of such groove; a plate hook for securing a printing plate on said bed, comprising a body block formed to fit in said groove; means projecting from the bottom of the block to engage one of said holes in the grooved bottom; obtusely pointed gripping pins adapted for protrusion from the sides of the block to engage the side walls of the groove, and means for protruding or releasing said gripping pins at will.

4. In combination with a printing press having a rectangular groove in its bed and a series of holes disposed at intervals in the bottom of such groove; a plate hook for securing a printing plate on said bed, comprising a body block formed to fit in said groove; means projecting from the bottom of the block to engage one of said holes in the groove bottom; a pair of headed pins mounted in the side walls of the block with their heads within said block, and a wedge member adapted to be forced between said heads for protruding said pins into gripping engagement with the side walls of the groove.

5. In combination with a printing press having a rectangular groove in its bed and a series of holes disposed at intervals in the bottom of such groove; a plate hook for securing a printing plate on said bed, comprising a body block formed to fit in said groove; means projecting from the bottom of the block to engage one of said holes in the groove bottom; a pair of headed pins

5 mounted in the side walls of the block with their heads within said block, and a screw in the block having a tapered portion positioned between the heads of said pins and adapted to wedge the pins apart and into engagement with the side walls of the groove when said screw is advanced in the block.

6. In combination with a printing press having a rectangular groove in its bed and 10 a series of holes disposed at intervals in the bottom of such groove; a plate hook for securing a printing plate on said bed, comprising a body block formed to fit in said groove, and a screw mounted in the block 15 having a reduced end portion dimensioned to fit any one of said holes in the groove bottom, said screw being mounted for up-and-down adjustment in the block for varying the protrusion of its reduced end therefrom.

7. In combination with a printing press having a rectangular groove in its bed and a series of holes disposed at intervals in the bottom of such groove; a plate hook for securing a printing plate on said bed, comprising a body block formed to fit in said groove; a screw mounted in the block having a reduced end portion dimensioned to fit any one of said holes in the groove bottom, said screw being mounted for up-and-down adjustment in the block for varying the protrusion of its reduced end therefrom; and gripping 25 devices adapted for protrusion in respectively opposite directions from the sides of the

block for engaging the side walls of the 35 groove, the said screw having a tapered portion adapted to act as a wedge for effecting such protrusion of the gripping devices.

8. In combination with a printing press having a rectangular groove in its bed and 40 a series of holes disposed at intervals in the bottom of such groove; a plate hook for securing a printing plate on said bed, comprising a body block formed to fit in said groove; a screw mounted in the block having a reduced end portion dimensioned to fit any one of said holes in the groove bottom, said screw being mounted for up-and-down adjustment in the block for varying the protrusion of its reduced end therefrom; said 45 screw having a tapered portion and gripping pins mounted in the block in position to be protruded laterally therefrom for engaging the side walls of the groove when said tapered portion of the screw is advanced between said pins, the reduced end of the screw protruding normally a slight distance from the bottom of the block and being farther protruded by such advance of the screw for protruding the gripping pins.

In testimony whereof, I have hereunto set my hand at Chicago, Illinois, this 18th day of December, 1915.

JOHN W. PITT.
